WELDER'S HOOD

Filed Oct. 11, 1930

FIG - 1 -

UNITED STATES PATENT OFFICE

JOHN S. NORTON, OF SAN FRANCISCO, CALIFORNIA

WELDER'S HOOD

Application filed October 11, 1930. Serial No. 488,122.

My invention relates to improvements in welders' hoods, and it consists in the combinations, constructions and arrangements hereinafter described and claimed.

An object of my invention is to provide a welder's hood in which an eye shield section is movable in the plane of the front face of the hood by a chin-actuated means for uncovering the eye opening in the front face. The glare shield is held in raised position by means of a weighted trigger, and the operator can free the trigger from the shield by moving his head abruptly in a lateral direction, whereupon the shield will drop into closed position by gravity.

A further object of my invention is to provide a device of the type described which is simple in construction and which disposes the dark glass on the inside of the hood and the protecting glass on the outside of the hood.

Other objects and advantages will appear as the specification proceeds, and the novel features of the device will be particularly pointed out in the claims hereto annexed.

My invention is illustrated in the accompanying drawings, in which:

Figure 1 is a section along the line 1—1 of Figure 2.

Figure 2 is a front elevation of the device, and

Figure 3 is a rear elevation.

In carrying out my invention I make use of a standard hood indicated generally at 1 and having a front face 2. The hood is supported upon the head of the operator by a headpiece 3. The parts thus far described are standard in construction and form no part of my invention except insofar as they cooperate with the parts now to be described.

The front face 2 has an opening 4 which is disposed at the level of the operator's eyes. A glare shield indicated generally at 5 is slideable across the opening 4 and is constructed in the following manner.

An outer member 6 is slideable on the outer face of the portion 2 of the hood, and this member has flanged edges 7 for reinforcing it. The side flanges 7' slidably engage with guides 8 that are secured to the face 2. The

bottom flange 7 rests against a stop 9 which is also secured to the face 2.

The piece 6 is secured to a U-shaped member 10 that is disposed on the inner face of the part 2 and is spaced from the piece 6 by a U-shaped spacing member 11. The outer sides of the member 11 bear against the sides of the opening 4 and guide the glare shield 5 in its movement.

The glare shield carries glasses which cover an opening 12 in the piece 6. A dark glass 13 is disposed on the inside of the glare shield and is secured to the U-shaped member 10 by side clips 14 (see Figure 3) and a bottom clip 15. A clear protecting glass 16 (see Figure 2) is disposed on the outside of the glare shield 5 and is secured to the piece 6 by side clips 17 and a bottom clip 18. These glasses are removable so that new ones can be substituted when desired. The piece 6 covers the opening 4 when the glare shield 5 is in its lowermost position with the exception of the opening 12, and this opening is covered by the glasses 13 and 16.

The means for raising the glare shield 5 vertically is shown in Figures 1 and 3. Arms 19 are pivoted to the U-shaped member 10 and are disposed beyond the sides of the glass 13 so as not to interfere with the vision. These arms are connected to levers 20 that are pivoted at 21 to a support 22, the latter being secured to the inner face of the part 2. Links 23 are secured to the inner ends of the levers 20 and have their other ends secured to an enlarged end 24 of a pull rod 25. The rod 25 is guided in a sleeve 26 that is carried by the support 22.

An adjustable chin rest 27 is carried by the rod 25 and is secured in adjusted position along a rack 28 formed in the rod 25.

I also provide means for supporting the glare shield 5 in raised position, and this comprises a weighted trigger 29 (see Figure 3) pivoted at 30 and having a cam edge 31 and a top edge 32. A pin 33 is carried by the glare shield 5, and the upward movement of the shield will cause the pin 33 to engage with the cam edge 31 and swing the trigger 29 in a clockwise direction about its pivot 30. The trigger will swing back into the position

shown in Figure 3 when the pin 33 clears the edge 31. A freeing of the glare shield 5 will now cause it to move downwardly until the pin 33 rests upon the top edge 32. The trigger 29 will now support the glare shield in raised position.

From the foregoing description of the various parts of the device, the operation thereof may be readily understood.

- 10 The hood is adjusted on the operator's head in the usual manner, and the chin rest 27 is raised so as to lightly contact with the chain of the operator. The weight of the glare shield 5 will hold it in closed position, 15 and the operator's eyes will be protected by the glasses 13 and 16.

When the operator wishes to raise the glare shield, he moves the chin rest 27 downwardly, and this, through the mechanism already described, raises the glare shield and uncovers the lower part of the opening 4. The operator can now check the work. The trigger 29 supports the glare shield in raised position as long as the operator desires.

- 25 In releasing the glare shield, the operator moves his head abruptly in a lateral direction, which causes the weighted trigger 29 to move in a clockwise direction about the pivot 30 and to free the pin 33. The glare shield 30 5 will now drop into closed position by gravity.

Although I have shown and described one embodiment of my invention, it is to be understood that the same is susceptible of 35 various changes, and I reserve the right to employ such changes as may come within the scope of the claims hereto annexed.

I claim:

1. The combination with a welder's hood 40 having a front face with an opening for the eyes therein, of a glare shield normally covering the opening, chin actuated means for sliding the shield along the hood surface into open position and comprising arms pivoted 45 to the sides of the shield, levers connected to the arms, links connected to the levers, and a bar connected to the links and having a chin support extending beneath the chin.

2. The combination with a welder's hood 50 having a front face with a sight opening therein, of a glare shield normally covering the opening, means for moving the shield in the plane of the front face of the hood for uncovering the opening, a member engage- 55 able with the shield for holding the latter in open position and being releasable from engagement when the hood is moved abruptly in a lateral direction.

Signed at San Francisco in the county of 60 San Francisco and State of California this 6th day of October, A. D. 1930.

JOHN S. NORTON.
